UNITED STATES PATENT OFFICE.

ANNETTA T. MOELLER, OF INDIANAPOLIS, INDIANA.

POWDER PUFF.

Application filed June 19, 1920. Serial No. 390,142.

To all whom it may concern:

Be it known that I, ANNETTA T. MOELLER, a citizen of the United States, residing at Indianapolis, in the county of Marion and 5 State of Indiana, have invented certain new and useful Improvements in Powder Puffs, of which the following is a specification.

The object of my said invention is to provide a powder puff which may be carried in 10 a hand-bag and kept clean and sanitary and also one embodying in a single structure a multiple of devices, thereby contributing to the compactness, convenience, and economy of its structure, as well as to its sanitary 15 characteristics, all as will be hereinafter more fully described and claimed.

Referring to the accompanying drawings, which are made a part hereof, and on which similar reference characters indicate similar 20 parts,

Figure 1 is a view showing a powder puff of my improved construction, with the soft surface inside and one flap open or turned back, and

25 Figure 2 a view showing the puff turned. Said powder puff consists of a sack-like device covered on one side with silk, or other smooth surfaced fabric A, adapted to furnish protection against dirt, etc., and the 30 other side covered with wool, eider-down, swan's-down, or any other material B appropriate for such use. The puff is preferably composed of two substantially duplicate parts the edges of which are stitched 35 together for somewhat more than half the circumference thereof, as to points 15 and 16, and the remainder left open, forming flaps adapted to be secured together by a snap fastener 10, such as a glove fastener, as 40 shown.

In one side of the outside of the structure is formed a pocket 11 in which is mounted 45 an auxiliary puff 12 intended for use as a rouge puff, thus combining with the main powder puff an auxiliary puff in convenient form for use.

When it is to be used, the main powder puff is turned to bring the soft side B out and when not in use it is turned to bring the 50 smooth side A out, which at such times brings the powdered side, containing the powder, within the enclosure and protects same from dirt, etc., maintaining the same in a sanitary condition.

Having thus fully described my said invention, what I claim as new and desire to 55 secure by Letters Patent is:

1. A powder puff consisting of two substantially duplicate circular outer parts of smooth material and two similar circular inner parts of soft fluffy material, the edges of which are stitched together for somewhat more than half of the circumference thereof, the remainder of the circumference being left open to provide for turning the puff inside out, the portion normally inside being formed for use as a powder puff and the portion on the outside forming a protecting means to prevent escape of the powder, substantially as set forth. 70

2. A circular powder puff adapted to be turned inside out, the portion normally inside adapted for use as a powder puff and the portion normally outside being formed of material adapted to serve as an ornamental protecting covering for the powder puff and a pocket for a rouge puff symmetrically placed on said covering and forming an ornamental feature thereof. 75

3. A powder puff comprising a pair of 80 substantially duplicate circular parts, each having on one side a material relatively impervious to powder and having on the other side a soft fluffy material adapted to retain powder between its component fibers, the 85 said materials of each of said parts being stitched together the entire length of the circumference thereof, one of the parts being stitched to the other for somewhat more than half the circumference thereof and the 90 remainder left open to provide for turning the puff inside out, substantially as set forth. 90

4. A circular powder puff adapted to be turned inside out, the portion normally inside adapted for use as a powder puff and 95 the portion normally outside being formed of material adapted to serve as a protecting cover for the powder puff and a pocket for a rouge puff placed on said covering, substantially as set forth. 100

In witness whereof, I have hereunto set my hand and seal at Indianapolis, Indiana this 16th day of June, A. D. nineteen hundred and twenty.

ANNETTA T. MOELLER. [L. S.]
